(57) **CLAIM**

The ornamental design for a wheeled case, as shown and described.

DESCRIPTION

Figure 1.1 is a perspective view of a wheeled case showing the new design.

Figure 1.2 is a left side view of the wheeled case.

Figure 1.3 is a back view of the wheeled case.

Figure 1.4 is a right side view of the wheeled case.

Figure 1.5 is a bottom view of the wheeled case.

Figure 1.6 is a front view of the wheeled case.

Figure 1.7 is a top view of the wheeled case.

The broken lines shown in the Figures show portions of the wheeled case that form no part of the claimed design.
